UNITED STATES PATENT OFFICE.

WARREN McARTHUR, JR., OF CHICAGO, ILLINOIS.

DESIGN FOR A TUBULAR LANTERN.

42,488.

Specification for Design.

Patented May 7, 1912.

Application filed February 7, 1912. Serial No. 676,151. Term of patent 14 years.

To all whom it may concern:

Be it known that I, WARREN McARTHUR, Jr., a citizen of the United States, residing at Chicago, in the county of Cook and State of Illinois, have invented a new, original, and ornamental Design for Tubular Lanterns, of which the following is a specification.

The accompanying drawing represents a perspective view of a tubular lantern embodying this design.

The characteristic feature of this design

consists of the upwardly contracted or downwardly flaring shape of the chimney A which extends from the globe B to the top C of the lantern frame.

I claim:

The ornamental design for a tubular lantern as shown and described.

WARREN McARTHUR, JR.
